DISPLAY APPLIANCE

James Thomas Powers, Jr., Chicago Heights, Ill.,
assignor to Funk Forging Company, Chicago
Heights, Ill., a corporation of Illinois

Application February 11, 1948, Serial No. 7,670

6 Claims. (Cl. 24—66)

1

The present invention pertains to or concerns certain innovative beneficial structural features and resulting functional advantages in display appliances, such as a new device which securely holds signs or papers or analogous posters in frames without the employment of any bolts, nuts or screws.

A paramount aim or substantial object of this invention is to provide an exhibit apparatus of this character which is simple in structure, which is relatively inexpensive to make and hence can be sold at a comparatively low amount, which performs its service efficiently and entirely satisfactorily, which is unlikely to become damaged or injured in ordinary employment, which is composed of few easily operated parts, but which nevertheless allows the display sheet or sheets to be inserted in place or removed therefrom with facility and ease, other accomplished designs of the device becoming apparent from the following description of the structure and mode of operation of a desirable incorporation of the invention in physical form.

In order that those skilled in, or acquainted with, this art may understand the structural details of the novel apparatus and comprehend the functional operative advantages and benefits accruing therefrom, a preferred embodiment of the invention at the present time has been fully illustrated in the accompanying drawing forming a part of this specification, its composition and mode of operation being described below.

In this drawing:

Figure 1 is a perspective view of the new holder displaying a paper sheet or poster;

Figure 2 is a central, vertical section on line 2—2 of Figure 1 on an enlarged scale;

Figure 3 is a front elevation of the construction shown in Figure 1 on approximately the same scale as that of Figure 2;

Figure 4 is a top plan view of the appliance depicted in Figure 3; and

Figure 5 is a partial cross-section on line 5—5 of Figure 3.

Referring to the several views of the drawing, in which like reference numerals have been employed to designate the same elements throughout, it will be perceived that the new holder includes a back, rearwardly facing, horizontal, angle-bar 11 and a companion, registered, front, forwardly facing, horizontal angle-bar 12 preferably, but not necessarily, of like sizes and shapes, the upstanding flanges of such pair of allied bars accommodating between them the top portion only of a thin, rigid, depending backing-plate

2

13 of any suitable material, such as metal, plastic, or comparable material, these three members being fixedly united together near their opposite ends by a pair of rivets 14, 14.

The central portion of the horizontal outstanding flange of the front angle-bar 12 has a longitudinal, rectangular slot 15 through it with the straight back-wall of such opening in near register with the front surface of the upstanding flange of such angle-bar.

Against the middle portion of the forward surface of such upright flange of angle-bar 12 an oscillatory disc-cam 16 is rockingly mounted on a suitable stud 17, such cam, ordinarily of metal, 15 consisting of a substantially flat, main body 18 equipped along one curved or arcuate edge with a correspondingly shaped outstanding marginal rib 19 of uniformly tapered width, thus providing its edge with a cam conformation 16, 20 another portion of such body 18 having a forwardly extending handle 21 by means of which the cam may be manually rocked on its axis.

This cam member, when in clamping position as shown in the drawing, projects in substantial 25 measure down through the opening or slot 15, and when not in action it may be rocked up about its axis so as to be entirely above the slotted flange.

The one or more display-sheets or posters 22 to 30 be exhibited while supported by this new holder has the top portion held in front of the plate 13 and a flat metal or comparable rectangular clamp 23 of any suitable size or shape is applied in front thereof while the clamp 23 is above the horizontal flange or bar 12 and then the cam is manually 35 rocked counter-clockwise down through the opening 15 by its handle 21 until the cam outer edge 16 of rib 19 by engagement with the outer wall of the opening 15 clamps the sheet or sheets 40 firmly in place.

When it is desired to release the poster or sheet the cam is turned clockwise until it frees both the poster and the clamping member 23.

As will be readily understood this poster sustaining member is supported by any approved means, not shown.

In order to reduce the friction between the oscillatory cam member 18 and the upright surface of the angle-bar 12 such member may be deformed to provide a round boss on its back and a corresponding depression on its front accommodating the forward head of the rivet 17, as clearly portrayed in Figure 5.

In many cases, it is preferred to provide the 55 back surface of the member 18 just inside its

cam rib 19 with a shallow curved bead 20 to engage the face of the clamp 23, such bead being formed by supplying the front face of the member 18 with a corresponding curved depression.

To those acquainted with this art it will be obvious that the present invention is not necessarily strictly limited and confined to the exact details of structure illustrated and described and that reasonable modifications may be resorted to without departure from the heart and essence of the invention or the loss of any of its substantial benefits and advantages.

I claim:

1. In a display holder, the novel combination of an angle-bar having an aperture through one flange, a cam-member, means rockingly mounting said cam-member on the adjacent face of the other flange of the bar and adapted to project through said aperture, a fixedly mounted backing-sheet depending from said angle-bar, and a clamp-member, said cam-member being adapted to be rocked manually through said aperture and engage said clamp-member to secure a display-sheet between said clamp-member and said backing-sheet by reason of the action of the cam-surface of said cam-member bearing on a wall of said aperture.

2. The novel combination set forth in claim 1, in which said cam-member includes a rockingly mounted main body, an outstanding rib having a cam-edge and a handle by which said member may be manually rocked.

3. The novel combination set forth in claim 2, in which said aperture has a first wall in substantial register with the adjacent face of said other flange and a second wall substantially parallel to said first wall and on which said cam bears.

4. The novel combination set forth in claim 1, in which said backing-plate is mounted on the back of said angle-bar and depends therefrom.

5. The novel combination set forth in claim 1, in which said cam-member has a depression in its front face accommodating a portion of its mounting means and has on its back face a complementary boss bearing against the front face of the angle-bar.

6. The novel combination set forth in claim 1, in which the portion of said cam-member which bears on said clamp-member has an outstanding hollow rib engaging the clamp-member.
